Primary Examiner — Manpreet Matharu*Assistant Examiner* — Keith Wilson(74) *Attorney, Agent, or Firm* — Banner & Witcoff, Ltd.(57) **CLAIM**

The ornamental design for a shirt, as shown and described.

DESCRIPTION

FIG. 1 is a front perspective view of a shirt showing our new design in an in-use configuration;

FIG. 2 is a front view thereof;

FIG. 3 is a left side view thereof;

FIG. 4 is a right side view thereof;

FIG. 5 is a top view thereof; and,

FIG. 6 is an enlarged view of the claimed region in FIG. 2, shown in isolation.

The broken lines immediately adjacent to the shaded area represent unclaimed boundaries of the design. The broken lines showing the remainder of the shirt are for environmental purposes only and form no part of the claimed design.
